UNITED STATES PATENT OFFICE.

GEORGE EDWARD JAMES STREET, OF KINGSTON, ENGLAND.

ILLUMINATING COMPOUND.

SPECIFICATION forming part of Letters Patent No. 695,123, dated March 11, 1902.

Application filed August 3, 1901. Serial No. 70,715. (No specimens.)

To all whom it may concern:

Be it known that I, GEORGE EDWARD JAMES STREET, of no occupation, a subject of the King of Great Britain, residing at Elm Villa, 5 Knight's Park, Kingston, county of Surrey, England, have invented certain new and useful Improvements in Illuminating Compounds, of which the following is a specification.

10 This invention has reference to illuminating compounds for consumption in fairy or bucket lamps or lamps for ornamental illumination; and its object is to produce a new type of oil which is peculiarly adapted for use 15 in such lamps.

It is well known that lamps of the kind in question consuming any of the oils hitherto used for same are very dirty in burning and smoke to such an extent as not only to give 20 rise to a very unpleasant smell, but also to spoil the ornamental effect they are intended to produce. Further, the light given by such lamps is comparatively dim and they are very liable to be prematurely extinguished. I have 25 devoted a great deal of time in experimenting with the object to produce a compound which should overcome these drawbacks, and I have at length succeeded in producing a type of oil or compound which effects this object in a most satisfactory manner. The improved type of illuminant burns with a clean 30 brilliant smokeless flame, evolving no unpleasant smell and producing a most pleasing effect from an illuminating point of view.

35 Lamps charged with the improved compound

will continue to burn with unimpaired brilliancy and cleanliness until the charge is entirely consumed, and, moreover, they will burn for a much longer time than is possible with any of the oils hitherto used for such 40 lamps.

The improved type of illuminant which constitutes the subject of this invention consists of a mixture of lard-oil and neat's-foot oil with or without camphor. I prefer to mix 45 these ingredients in about the following proportions: three-fourths pint of lard-oil, one-fourth pint of neat's-foot oil, and when camphor is used one-half ounce camphor. It will, however, be understood that I do not limit 50 myself to these exact proportions, which may be varied.

What I claim, and desire to secure by Letters Patent, is—

1. An illuminating compound for fairy- 55 lamps, bucket-lamps or lamps for ornamental illumination, containing a mixture of lard-oil and neat's-foot oil.

2. An illuminating compound for fairy- 60 lamps, bucket-lamps or lamps for ornamental illumination, consisting of a mixture of lard-oil, neat's-foot oil and camphor.

In witness whereof I have hereunto signed my name in the presence of two subscribing witnesses.

GEORGE EDWARD JAMES STREET.

Witnesses:

REGINALD EATON ELLIS,
THOMAS LAING WHITEHEAD.
